UNITED STATES PATENT OFFICE.

HARRY T. KEEL, OF CHESTER, PENNSYLVANIA.

DESIGN FOR A PACKAGE-TIE.

47,042.

Specification for Design.

Patented Mar. 2, 1915.

Application filed November 24, 1914. Serial No. 873,837. Term of patent 14 years.

To all whom it may concern:

Be it known that I, HARRY T. KEEL, a citizen of the United States, residing at Chester, in the county of Delaware and State of Pennsylvania, have invented a new, original, and ornamental Design for Package-Ties, of which the following is a specification, reference being had to the accompanying drawing, forming a part thereof.

The figure is a perspective view of a package tie, showing my new design.

I claim:

The ornamental design for a package tie, as shown.

HARRY T. KEEL.
